UNITED STATES PATENT OFFICE.

EUGENE SEMPLE BRADFORD, OF NEW YORK, N. Y., ASSIGNOR, BY MESNE ASSIGNMENTS, TO THE STEEL PLATE PRINTING COMPANY, OF CAMDEN, NEW JERSEY.

PLATE-PRINTING MACHINE.

SPECIFICATION forming part of Letters Patent No. 625,315, dated May 23, 1899.

Application filed September 24, 1898. Serial No. 691,756. (No model.)

To all whom it may concern:

Be it known that I, EUGENE SEMPLE BRADFORD, a citizen of the United States, residing at the city of New York, in the county of New York and State of New York, have invented certain new and useful Improvements in Wiping and Polishing Mechanism for Printing-Presses, of which the following is a specification.

10 My invention has relation to printing-presses, and particularly to those of the rotary-plate type, and it comprises in such connection improvements in plate wiping and polishing devices or mechanisms for printing-presses.

15 My invention, stated in general terms, consists of the improvements in printing-presses when constructed and arranged in substantially the manner hereinafter described and 20 claimed.

25 The nature and characteristic features of my present invention will be more fully understood from the following description, taken in connection with the accompanying drawings, forming part hereof, in which—

30 Figure 1 is a side elevation of a printing-press embodying main features of my invention with the plate-cylinder of the same occupying a position to the right of the printing-press. Fig. 2 is a top or plan view of Fig. 1, certain portions being broken away in order to more fully illustrate the polishing and wiping devices of the printing-press with the plate-cylinder shown in contact with the polishing device of my present invention. Fig. 3 is a detail view of the polishing device enlarged, illustrating the same in top or plan view. Fig. 4 is a side elevation, partly sectioned, of Fig. 3. Fig. 5 is a sectional view 35 on the line xx of Fig. 3. Fig. 6 is a sectional view on the line yy , reduced, of Fig. 4, looking toward the polisher-head. Fig. 7 is a sectional view on the line zz of Fig. 5. Fig. 8 is a view, partly in section and partly in elevation, of mechanism for controlling the operation of the polishing device. Fig. 9 is a view, partly in section and partly in elevation, at right angles to Fig. 8. Fig. 10 represents details thereof, and Figs. 11 and 12 40 are respectively views in longitudinal section and front elevation of a spool adapted to be

used in conjunction with the wiping and polishing devices.

Referring to the drawings, the plate-printing press or machine of my said invention comprises an impression-cylinder A and a plate-cylinder B, both suitably journaled in bearings in the framework C of the machine. The bearings w of the impression-cylinder are preferably supported in vertical guides w' , 55 and a spring w^2 and a set-screw w^3 are provided, whereby the position and pressure of the impression-cylinder A are readily and efficiently adjusted.

D represents a drag for wiping a printing-plate B' , carried by the printing-cylinder B of the printing-press, after it has been inked by the inking-rollers a and b of an inking apparatus fully described and shown in an application filed by me under date of January 9, 1899, and under the Serial No. 701,540. This device consists of a frame d , in which are mounted the shafts d' , the preferably square portion of which carries two spools d^2 , upon which an apron e is wound, as illustrated 75 in Fig. 1 of the drawings. The apron passes from one of the spools d^2 up over a roller e' , then down beneath a roller e^2 , supported on the frame d , then up over a roller e^3 , and then down to the other spool d^2 . The rollers e' and e^3 are in close proximity to the passing printing-plate B' , carried around by the printing-cylinder B, as illustrated in Fig. 1, so that the apron e wipes the face of the plate B' . These rollers e' and e^3 are supported on stems 80 e^4 , which pass loosely through the sleeves e^5 , secured to the frame d . Springs e^6 are placed between the sleeves e^5 and the heads of the rods e^4 , so as to keep the rollers e' and e^3 in their outer position with a spring-pressure, 85 and the lower ends of the rods e^4 are provided with thumb-nuts e^7 , by which the position of the rollers e' and e^3 may be adjusted.

On the shaft d' of one of the spools d^2 is mounted a ratchet-wheel e^8 , engaged by a 95 pawl e^9 on a lever e^{10} . This lever e^{10} is connected by a rod f to a crank-arm f' on the main shaft L of the press or machine. As the wheel revolves an oscillating movement is imparted to the lever e^{10} , causing the spool 100 d^2 to be intermittently turned by means of the ratchet-wheel e^8 , and thus the apron to be

5 moved at intervals from one of the spools d^2 onto the other and presenting thereby clean surfaces of the apron to the engraved plate B' each time the plate comes around. When the apron e has passed from one roller onto the other, it may be reversed and the other side of it used by changing the spool. The spools D² are held under tension in the frame d by means of pins d³, which are held inwardly by means of springs d⁴ pressing against their outer ends.

10 H represents a polisher for wiping the plate B' after it has been wiped by the drag D. But one of these polishers has been shown, yet it is to be understood that any desired number may be employed. The polisher shown is driven from the counter-shaft g, which is provided with a gear-wheel g', meshing with a pinion g² on the shaft g³, to which the driving-pulley g⁴ is secured, as illustrated in Figs. 1 and 2. The gear-wheel g' also meshes with a gear-wheel g⁵, that engages a pinion g⁶ on the shaft g⁷. On this shaft is a bevel-wheel g⁸, that engages with a bevel-wheel h. The bevel-wheel h of the polisher is formed upon or secured to a sleeve h', as illustrated in Fig. 4, and fits over and is splined to a shaft h² and turns with it, the shaft h² being capable, however, of longitudinal movement within the sleeve h'.

15 To the inner end of the shaft h² is secured the polisher-head h³, and surrounding the shaft h² is a spring h⁴, which serves to force the polisher-head always toward the plate-cylinder B.

20 The sleeve h' is held by and fits in a bracket or housing h⁵, supported on a block h⁶, as illustrated in Figs. 1, 2, 3, and 4. This block is held between standards i, as illustrated in Fig. 2, by means of bolts h⁷, fitting the slots i' in the upper ends of the standards. The housing h⁵ can be moved slightly endwise on the block h⁶, and the block can be moved in a vertical direction slightly by the bolts h⁷, fitting in the slots i' of the standards, whereby the face of the polisher can be readily adjusted with relation to the surface it has to operate upon.

25 h⁸ represents a lever pivoted at h⁹ to the housing h⁵ and the outer end of which is forked to span the shaft h² and engage ball-bearing collars h¹⁰, fixed and movably connected with the shaft h². The inner end of the lever is forked to receive a threaded rod h¹¹, tapped into the housing h⁵, and which rod is provided with a thumb-nut h¹². By tightening the thumb-nut h¹² the lever h⁸ draws the shaft h², and consequently the polisher-head h³, away from the plate-cylinder B. By loosening the nut h¹² the shaft and the polisher-head will be forced toward the plate-cylinder B by means of the spring h⁴. The polisher-head is revolved by means of the gearing described, the rotation of the bevel-wheel h by the gear connections causing the polisher-head to rotate in a similar manner. The polisher-head h³ carries an apron h¹⁴, of suitable cloth, wound

30 on spools h¹⁵ and h¹⁶, and is of the same character as those for the wiper D. (Illustrated in Figs. 11 and 12.) The apron h¹⁴ passes over the front or face of the head h³, as illustrated in Fig. 4.

35 A tension device may be applied to the spool of ribbon or apron, such as a screw-pin h¹⁷, passing through the bearing of the shaft 75 h¹⁸ and bearing against said shaft and a spring h¹⁹ to resist the turning of said screw-pin h¹⁷.

40 For shifting or moving the ribbon or apron h¹⁴ in an intermittent manner is provided, preferably, a set of friction-wheels k, k', and 80 k², the friction-wheel k being splined in a sleeve k³, which is journaled on a fixed hub or hollow stud k⁴, projecting from the housing h⁵, and the friction-wheel k² being mounted on the shaft k⁵ of the polisher-head h³. 85 The shaft k⁵ is provided with a worm k⁶, preferably incased and indicated in dotted lines in Figs. 3 and 4, which engages with a worm-wheel k⁷ on the shaft h²⁰ of the apron mechanism, as shown in section in Fig. 5. The 90 intermediate friction-wheel k' is journaled on a support k⁸, projecting from the polisher-head h³. Semicircular brake-shoes k⁹ and k¹⁰, pivoted at k¹¹ and k¹² to the housing or frame h⁵, embrace the sleeve k³ and are normally held 95 apart by a spring k¹⁴, so as to release the sleeve and allow it to turn freely on the hub k⁴ of the housing h⁵. A shaft l carries a pin l', engaging with an inclined surface l³ on a collar l², fixed to one of the brake-shoes by a set-screw l⁴, and the outer end of the shaft l carries nuts l⁵, engaging with the other brake-shoe, so that as the shaft l is turned the pin l', riding upon an incline l³, forces the brake-shoes together, and thus checks the rotation 100 of the sleeve k³ and the friction-wheel k, splined thereon, as will be readily understood from Fig. 5 of the drawings. As the shaft h² is turned the polisher-head will be rapidly 105 revolved, polishing the plate B' of the plate-cylinder B, and the friction-wheels k' and k² will revolve around the center of the friction-wheel k, at the same time rotating the same, and the friction-wheels k' and k² will not revolve on their axis until the movement 110 of the friction-wheel k is checked by the brake-shoes k⁹ and k¹⁰, and when this takes place the friction-wheels k' and k² will be turned on their respective axes and the apron 115 shifted along the face of the polisher-head by 120 the action of the worm and worm-wheel.

125 The brake-shoes k⁹ and k¹⁰ are applied by the rocking of the shaft l. This is done by means of a crank l⁶ on the shaft l, which is pivotally connected to two rods m and m', 130 sliding in fixed guides m² and carrying pins or rollers m³, engaging with projections or tappets on the cam-drum n. The periphery of the cam-drum n has a groove n', in which is fixed a block or tappet n², that comes 130 against the roller m³ on the rod m and thereby rocks the shaft l in one direction and, by means of the pin l', working on the incline surface l³, closes the brake-shoes upon the hub

k^3 of the friction-wheel k and holds the pinion from turning, when, as already described, the apron will be shifted along the face of the polisher-head h^3 .

5 On the inner face of the cam-drum n is a projection or tappet n^3 , which engages with the pin or roller m^3 of the rod m' , and after the parts have been shifted, as above, thereby throws the rod m' and with it the crank l^6 and shaft l in the opposite direction to that in which they were moved by the tappet n^2 , thus releasing the pin l' from the incline l^3 and allowing the spring l^5 to separate the brake-shoes from the hub k^3 , whereupon the friction-wheel k rotates freely, as before, and the shifting of the apron ceases. The tappet-block n^2 is held in the groove n' of the cam-drum n by a flange on its inner end fitting into enlargements n^4 in the groove n' and is held to its adjustment by a pawl n^5 , pivoted thereto and which engages notches n^6 in one wall of the groove, the pawl being pressed into engagement with the notches by means of a spring n^7 and being drawn out of engagement with the notches when it is desired to adjust the blocks by means of the pin n^8 , projecting from the pawl n^4 , as illustrated in Figs. 8, 9, and 10 of the drawings.

In order to guide the apron h^{14} straight 30 while it is being drawn over the face of the polisher-head h^3 and keep it from crowding to one side or the other by reason of inequalities or deviation from the proper direction of the edges or ends of the polisher-head, there is provided an adjustable edge piece at one or both ends of the polisher-head, as illustrated in Figs. 4 and 6, wherein o represents such edge pieces secured to the polisher-head h^3 by means of bolts o' , passing through the 40 slots o^3 in such edge pieces. By loosening the bolts the edge pieces can be adjusted to exact perpendicularity to the line of travel of the apron, and by then tightening up the bolts the apron will be guided accurately, with no 45 tendency to crowd to one side or the other.

The object of the spline connection between the friction-wheel k and its hub k^3 is to permit the polisher-head h^3 , with the friction-wheels k , k' , and k^2 , to be moved longitudinally under the influence of the spring h^4 and the adjusting device without interfering with the friction-wheel connections.

Having thus described the nature and objects of my invention, what I claim as new, and desire to secure by Letters Patent, is—

1. In a machine of the character described, a rotatable cylinder adapted to receive and support a removable printing-plate, a rotary polisher provided with a head having an apron, 60 said polisher being pivotally supported at one end only and the other end free so that said head with its apron is adapted to occupy different angles of inclination with respect to the position of the printing-plate of said cylinder in action, substantially as and for the purposes described.

2. In a machine of the character described,

a rotatable cylinder adapted to receive and support a removable printing-plate, a rotary polisher provided with a head having an apron, 70 said polisher being pivotally supported at one end only and the other end free so that any portion of the apron of said head may be brought into contact with the printing-plate of said cylinder in action, and an edge piece 75 detachably and adjustably connected with either end of said head, substantially as and for the purposes described.

3. In a machine of the character described, a rotatable cylinder adapted to receive and support a removable printing-plate, a horizontally and vertically adjustable rotary polisher provided with a head carrying an apron, 80 said polisher being supported at one end only and a slotted edge piece adjustably connected 85 with either end of said head so as to prevent crowding of the apron of said head in the direction of rotation of the same, substantially as and for the purposes described.

4. In a machine of the character described, 90 a rotatable cylinder adapted to receive and support a removable printing-plate, a rotary polisher provided with a head carrying an apron, said polisher being pivotally supported at one end only and the other end free to 95 swing so as to bring any portion of said head with its apron into contact with the printing-plate of said cylinder, and adjustable guides consisting of slotted end pieces with bolts extending through the slots of said pieces into 100 the ends of said head, substantially as and for the purposes described.

5. In a machine of the character described, a polishing-apron, a polisher-head provided with apron-carrying devices, means for rotating the polisher-head, a housing in which the polisher-head is mounted, friction-brake devices mounted on said housing and friction-wheels engaging with one another and also 105 engaging with the brake and apron-carrying 110 devices, substantially as and for the purposes described.

6. In a machine of the character described, a frame, a pair of spools mounted in said frame, an apron adapted to be wound from 115 one spool onto the other, a pair of spring-pressed rollers over which said apron passes, an intermediate roller under which the apron passes, and means for moving one of the first-mentioned spools to shift said apron, substantially as and for the purposes described.

7. In a machine of the character described, a printing-plate cylinder, a pair of spools, an apron adapted to be wound from one spool onto the other, rods upon which said rollers 125 are mounted, a set-screw engaging said rods and a spring engaging said set-screw to prevent turning thereof and said set-screw adapted to maintain said apron taut and said rollers in such condition as to yield when said 130 apron is shifted, substantially as and for the purposes described.

8. In a machine of the character described, a frame, a pair of spools supported in said

frame, an apron adapted to be wound from one spool onto the other, a pair of rollers over which said apron passes, rods upon which said rollers are mounted, sleeves through which 5 said rods pass, nuts on the lower ends of said rods, and springs between said sleeves, and rollers over which said apron passes, substantially as and for the purposes described.

9. In a machine of the character described, 10 a polisher carrying an apron, means for actuating said polisher, and means for intermittently moving said apron, consisting of friction-wheels connected with the apron-carrying devices, a pair of brake-shoes applied to 15 one of said friction-wheels, one of said brake-shoes being provided with an inclined part, and means for applying the shoes consisting of a rock-shaft provided with a pin adapted to engage with the other brake-shoe, and means 20 for rocking said shaft, substantially as and for the purposes described.

10. In a machine of the character described, 25 a polisher-head, means for turning said polisher-head, means for intermittently moving an apron, consisting of friction-wheels connected to said polisher-head and a pair of 30 brake-shoes applied to the friction-wheels of the head, one of said brake-shoes being provided with an inclined part, and means for applying the shoe, consisting of a shaft pro-

vided with a pin adapted to engage said inclined part on one of the brake-shoes, and said shaft also engaging with the other brake-shoe, and means for rocking said shaft, said means connected with said crank, a grooved 35 wheel, and an adjustable block in said wheel, substantially as and for the purposes described.

11. In a machine of the character described, 40 a polisher having a gear-supporting housing, an operating-shaft passing through said housing, a lever pivoted to said housing and engaging with said shaft, and a set-screw for adjusting said lever, substantially as and for the purposes described.

12. In a machine of the character described, 45 a polisher having a housing, a shaft passing through said housing, a lever pivoted to said housing and engaging with said shaft, a threaded rod tapped in said housing, and a 50 thumb-nut on said rod for adjusting said lever, substantially as and for the purposes described.

In testimony whereof I have hereunto set my signature in the presence of two subscribers.
